(No Model.)

C. WHITEHALL.

CULTIVATOR.

No. 379,430.

Patented Mar. 13, 1888.

UNITED STATES PATENT OFFICE.

CURTIS WHITEHALL, OF MELLOTT, INDIANA.

CULTIVATOR.

SPECIFICATION forming part of Letters Patent No. 379,430, dated March 13, 1888.

Application filed August 22, 1887. Serial No. 247,555. (No model.)

To all whom it may concern:

Be it known that I, CURTIS WHITEHALL, of Mellott, in the county of Fountain, State of Indiana, have invented certain new and useful Improvements in Cultivators; and I do hereby declare the following to be a clear and exact description of the same.

This invention relates to that class of straddle-row cultivators in which the operator walks and guides the plows, which are arranged in gangs, so as to cultivate both sides of a row of plants at the same time.

My invention consists, chiefly, of a peculiar construction by which I obtain compound endless plow-beams having swinging lateral motion on their fastenings or pivots, obtaining simplicity, greater strength, and increased facility in working. I attain these objects by the mechanism shown in the accompanying 20 perspective view of my cultivator.

A A represent the wheels, and B B the axles. The saddle or arch C is preferably solid with the axles, the whole being formed of a continuous bar, shaped as shown.

25 D D show supports for the rear ends, a, of the tongue E, said ends being loosely secured about midway of their length to the arch or saddle C by staples a', so as to be vertically adjustable.

30 F is an ordinary yoke extending across and pivoted to the tongue E and loosely held by adjustable links b and couplings c to the struts d secured to the axles and arch, as indicated.

At the top of the saddle C is a spring-hanger, 35 G, to the ends of which are suspended, so as to be vertically adjustable, the hooks e. Sleeves or sockets f surround the horizontal parts f' of the arch, said sleeves or sockets being connected to back plates, g. From the back

plates, g, hooks h extend, which act in connection with the hooks e, as hereinafter stated. Each of the plow-beams H consists of two endless bars of iron, i, said beams being hinged in the back plates, g, as shown. At the opposite end of each of the compound plow-beams H is a plate, k, in which the endless bars i composing the compound beams are journaled and to which plate the shovels I are attached. The handles are represented by J, a handle being attached to each compound beam. 40 45 50

It will be seen that the compound beams have a lateral movement in the back plates, g, and that the two endless bars i of the beams H, by reason of their being journaled at each end, constantly maintain the same distance 55 apart.

This construction of beam gives to it great strength and permits of the adjustment of the plows with great facility. The hooks e and h and the spring-hanger G give a certain elasticity to the beams H, the tendency of the spring-hanger being to raise the beams. This elasticity can be varied by the adjustability 60 of the suspension-hooks e. When the plows are not in use, the beams H are raised and 65 held up by means of the hooks k.

Having described my invention, I claim—

In a wheel-cultivator, the arch C and compound beams H, hinged thereto and capable of lateral adjustment, combined with the spring-hanger G and hooks e h, substantially as set forth.

In testimony whereof I have hereunto set my hand and seal.

CURTIS WHITEHALL. [L. S.]
